(57) **CLAIM**

The ornamental design for a rowing machine, as shown and described.

DESCRIPTION

FIG. 1 is a front, top and left side perspective view of the first embodiment of a rowing machine, showing my new design;

FIG. 2 is a rear, bottom and right side perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of portion 9 shown in FIG. 1 thereof;

FIG. 10 is an enlarged view of portion 10 shown in FIG. 2 thereof;

FIG. 11 is an enlarged view of portion 11 shown in FIG. 2 thereof;

FIG. 12 is an enlarged view of portion 12 shown in FIG. 8 thereof; and,

FIG. 13 is an enlarged view of portion 13 shown in FIG. 8 thereof.

The dashed broken lines shown in the drawings depict portions of the rowing machine that form no part of the claimed design.

The dot-dash broken lines shown in FIGS. 1, 2, and 8-13 represent the designation of an enlargement view and form no part of the claim thereof.

1 Claim, 13 Drawing Sheets
